CLASP FOR GARMENT SUPPORTERS

John Robie Parker, Toronto, Ontario, Canada,
assignor of one-half to Fred Page Higgins,
Toronto, Ontario, Canada

Application March 27, 1934, Serial No. 717,620

3 Claims. (Cl. 24—245)

The invention relates to improvements in clasps for garment supporters as described in the present specification and shown in the accompanying drawing that forms a part of the same.

- 5 One object of the invention is to provide a clasp for garment supporters which will lie snugly against the limb of the wearer and will not present any protruding part, such as a stud, which would be apparent through the covering garment.
- 10 Another object is to provide a resilient support for the keeper which, when brought to a state of tension and placed in position over the hose and then released will cause said keeper to move into operating position in relation to the underlying 15 boss and which must also be tensioned in the removal of said keeper whereby accidental dislodgement of said keeper is prevented.

20 A still further object is to provide a clasp of such a nature that the gripping strain on the hose, or other garment, will be distributed over a large area and thereby reduce to a minimum the danger of injuring the garment.

25 And generally the objects of the invention are to provide a simple and durable clasp which can be easily and quickly adjusted and which will be neat in appearance and cheap to produce.

30 With the above and several objects in view my invention consists in the novel features of construction, combinations and arrangements of parts described in the present specification and more particularly pointed out in the claims for novelty following.

35 In the drawing Figure 1 is a front view of a portion of a limb showing the clasp in gripping engagement with a stocking.

Figure 2 is a front view of the clasp shown in Figure 1 with the keeper raised against its resilient support into position preparatory to gripping the hose.

40 Figure 3 is a rear view of the clasp with the support for the keeper relaxed as in the operative condition of the device.

Figure 4 is a cross sectional view taken on the line 4—4 of Figure 1.

45 Figure 5 is a front view of a modified form of the invention shown in gripping relation to a stocking.

Figure 6 is a front view of the clasp shown in Figure 5 with the keeper support distended preparatory to moving into position to grip the stocking.

50 Figure 7 is a side view of the structure shown in Figure 6, partly in cross section.

55 Figure 8 is a cross sectional view taken on the line 8—8 of Figure 7.

Figure 9 is a front view of a further modification of the invention.

Figure 10 is a front view of a still further modified form of clasp.

Figure 11 is a longitudinal sectional view taken on the line 11—11 of Figure 10.

Like numerals of reference indicate corresponding parts in the various figures.

Referring to the drawing, 1 designates a plate which may be of celluloid, metal or any other suitable material and which is preferably concavo-convex in cross section to conform to the shape of a limb, said plate having a transverse slot 2 at the top end thereof for the reception of a tape 2a, or other element, from the supporting garment and at the lower end thereof having an upwardly tapering substantially triangular boss 3 on the outer face thereof and over which the top portion of the hose is adapted to be placed, which boss is provided with grooves 4 20 in the opposite side edges thereof. The plate 1 is also provided with a longitudinally arranged slot, or opening, 5 positioned between the top end of the boss 3 and the transverse slot 2.

6 designates a keeper which is provided with an upwardly reducing triangular shaped opening 7 adapted to receive the boss 3 and that portion of the hose positioned over said boss, said opening being reduced in conformity with the solid portion of the boss between the grooves 4 so that when the keeper is placed over the boss it may be moved downwardly to bring the portions 8 at each side of said opening into said grooves and thereby securely clamp the hose to the boss. The keeper 6 may be closed at its lower end as shown at 9 in Figures 1, 2, and 3, in which case the opening 7 in the keeper is considerably longer than the boss 3 to permit of the insertion of the boss in the enlarged lower end of said opening, or, the lower end of the keeper may be left open as shown in Figure 9.

The keeper 6 is resiliently connected to the plate 1 by means of an elastic member 10 which is secured at one end to the inner face of said plate at a point below the slot 5, as at 11, and extends upwardly and through said slot 5 and is secured at its other end to the top end of the keeper, as at 12, said elastic member being of such length that when in its relaxed condition the relation of the opening 7 in the keeper to the boss 3 is such that the said boss will not enter said opening, so that when it is desired to clamp the hose to the boss it is necessary to move the keeper or the plate 1 in relation to one another against the tension of said elastic member to bring said 55

boss into position to enter said opening, upon which the elastic, when permitted to do so, will rebound to its relaxed condition and cause the keeper to close around the said boss and securely grip the hose. In like manner the elastic member 10 must be tensioned in order to permit of withdrawal of the keeper from the boss to release the hose and this necessity to tension the elastic member provides an effectual preventative against accidental dislodgement of the keeper as the parts are of such thin material and are so constructed in relation to each other that it is extremely difficult to accidentally strike the lower end of the keeper upwardly with sufficient force to counteract the resistance offered by the elastic member.

In Figures 5 to 8 inclusive a modified form of construction is shown in which the keeper 13 consists of upper and lower walls 15 and 16 respectively, spaced from one another, with the lower wall at least having an upwardly reducing triangular opening 17 therein from the lower end thereof providing flanges 18 adapted to slide within the grooves in the opposite side edges of the boss, or block, 19.

In the operation of the latterly described device it is obvious that to bring the keeper into gripping relation to the hose it is simply necessary to move the keeper 13 and the boss 19 away from one another against the tension of the elastic member sufficiently far to permit of the boss entering the opening in the lower end of the keeper and upon release the said elastic will rebound and draw said boss and said keeper into interlocking engagement with each other with the hose securely held therebetween.

In Figures 10 and 11 a further modification is shown in which the keeper 20 is suspended from the supporting garment and has a downwardly reducing triangular shaped opening 21 providing opposing walls 22 adapted to slide in opposed grooves in the side edges of a tapering triangular shaped boss, or block, 23 carried by a plate 24, which keeper and plate are resiliently connected by an elastic member 25 secured at one end to the keeper above the opening 21 and extending upwardly and secured at its other end to the said plate 24. In this case the keeper and the plate are moved in relation to one another against the tension of the elastic member until the boss is in position to enter the opening 21, after which the elastic member operates as previously described to bring the keeper and the boss together over the hose.

In the construction of the clasp it is preferable that all of the various parts be made concavo-

convex in cross section to snugly fit the limb of the wearer.

While the preferred embodiment of the present invention has been herein shown and described it is of course to be understood that alterations in details of construction and arrangements of parts as comes within the scope of the following claims for novelty may be made.

What I claim is:—

1. A clasp for garment supporters comprising a plate having a triangular boss on the outer face thereof, said boss being grooved along its opposite side edges, said plate also having a slot therein above said boss, a keeper having a triangular shaped opening therethrough adapted to receive said boss, said keeper being slid longitudinally in relation to said boss to bring the opposite side walls of said opening into said grooves in said boss, an elastic element secured at one end to said plate below said opening therein and extending through said opening and secured at its other end to said keeper above the point of connection with said plate, said elastic element being of such length that in the gripping position of the clasp it will be in a relaxed condition and in the movement of said keeper to and from its gripping position offering resistance thereagainst.

2. A clasp for garment supporters comprising a plate having a triangular boss on the outer face thereof adapted to underlie the garment to be supported, said boss being grooved along its opposite side edges, said plate being concavo-convex in cross section, said plate also having a slot therein above said boss, a keeper having a triangular shaped opening adapted to receive said boss and sliding longitudinally thereof into locking engagement with said boss, said keeper being concavo-convex in cross section, and elastic means adapted to move said keeper into gripping relation with said boss subsequent to the insertion of said boss in said opening.

3. A clasp for garment supporters comprising a plate having a boss on the outer face thereof, said plate having a slot therein above said boss, a keeper having an opening therethrough adapted to receive said boss, an elastic element secured at one end to said plate below said opening therein and extending through said opening and secured at its other end to said keeper above the point of connection with said plate, said elastic element being of such length that in the gripping position of the clasp it will be in a relaxed condition and in the movement of said keeper to and from its gripping position offering resistance thereagainst.

JOHN ROBIE PARKER. 55
